UNIVERSAL SEAT PAD

Filed July 11, 1932

By: *Edward Wittcoff*
Dr. Hale G. Pitty.

UNITED STATES PATENT OFFICE

1,997,027

UNIVERSAL SEAT PAD

Edward Wittcoff, St. Louis, Mo.

Application July 11, 1932, Serial No. 621,849

2 Claims. (Cl. 155—182)

This invention relates to improvements in seat covers or shields, having for an object to provide a device of the character stated, particularly advantageous for usage in connection with the seat and back cushions of motor-driven vehicle seats, chairs and the like, so constructed that the same can be adjusted to effect a tailored-like or snug fit with respect to a seat or back upon which it is used, hence, assuring a neat and efficient covering or shielding thereof.

An equally important object of the invention is to provide a seat cover or shield constructed in a manner whereby it may be practically and efficiently used upon seats or backs of different lengths, by reason of the adjustable characteristics thereof, thus, rendering it universal in its range of usage and eliminating the necessity of making such a device in many different lengths in order to be satisfactorily usable in connection with seats, backs and like surfaces of different lengths.

It is also an object of the invention to provide a shield, or as it is often times designated in the trade, a seat pad, which, when properly adjusted and engaged over the exposed surface of a seat or its back, will snugly or embracingly engage the same, portions thereof engaging over the sides of said seat or back and thereby, effecting an engagement or fit which in addition to being snug and tailored-like in appearance, will prevent undesirable shifting of the shield with respect to the seat or back, and accordingly, avoid its displacement when in use.

Heretofore, in the manufacture of seat covers or shields particularly adapted for use upon the upholstered seat and back cushions of the seats of automobiles, it has been the custom or practice to make the same of different lengths in order that they will effectually and satisfactorily cover the surfaces of the cushions to be protected and which, as will be understood, are made of different lengths or sizes. This heretofore prevalent practice has required that the manufacturer and the retailer make up and carry in stock, a great number of different sizes of shields subject to trade calls, with the result that the ultimate costs of the devices are materially increased. Through the medium of my invention, I am enabled to produce a cover or shield which is more or less universal in its range of usage in that a single shield can be readily adjusted to effectually fit practically any lengths of seat and back cushions used in the different designs of automobiles and when fitted to a seat or back cushion,

will cover and protect the top surface thereof and its sides as well, due to its embracing engagement therewith. Not only does this mode of engagement of the shield with the cushions afford greater protection thereof, but it will also be understood that due to its snug or embracing engagement with the cushion, the shield will be positively engaged with the cushion throughout its entire period of usage.

From the foregoing, it will manifest itself to workers skilled in this art that my improved cover or shield will afford a means whereby the stock of a manufacturer and/or retailer may be considerably reduced, hence, effecting a material saving in invested capital; furthermore, that the constructional characteristics of the improved device are such that the same will afford greater advantages and utilities.

Other objects of the invention will be in part obvious and in part pointed out hereinafter.

In order that the invention and its mode of operation may be readily understood by those skilled in the art to which it appertains, I have in the accompanying drawing and in the detailed description based thereupon, set out several embodiments of my invention.

In the drawing:

Figure 1 is a perspective illustrating the manner in which the improved shields are engaged in operative position and positioned with respect to the seat and back cushions of an automobile seat;

Figure 2 is a plan view of the invention having parts thereof broken away and shown in section, and,

Figure 3 is a fragmentary longitudinal section taken through a portion of one of the improved shields illustrating, in full lines, the arrangement of the same with respect to a seat or back prior to adjusting the same and also illustrating, in dotted lines, the position of the extremity of the shield when in a flexed or adjusted position with respect to a seat or back.

Having more particular reference to the drawing, in connection with which like characters of reference will designate corresponding parts throughout, it is to be understood, at the outset, that whereas I have shown and described the invention as applied to a seat cover or shield including relatively assembled or interconnected seat and back sections 1 and 2 and a so-called kick-apron 3, the application of the invention is not necessarily limited to such an arrangement or assembly. To the contrary, the invention may be equally well used in connection with individual sections, whether for a seat or its back, or for an

individual kick-apron, should the occasion require. The accompanying showing is purely illustrative of a satisfactory embodiment of the invention, wherein the sections 1 and 2 are of rectangular formation and consist of flexible sheet-like bodies of material of composition or woven structure. The bodies, when woven, may be of fabric, though in the present embodiment, they are shown to be constructed of straw matting, as is the kick-apron 3. Where woven materials, and especially, straw matting, are utilized in the making of the sections, aforesaid, the warp elements or straws extend transversely of such sections, while the woof straws thereof are longitudinally disposed. Of course, the arrangement of the woof and warp elements, as just described, need not necessarily follow in connection with sections which are made of comparatively fine fabrics, though in the instance of straw matting usage, this arrangement is preferable in order that flexing of the straw matting sections may be effected without breakage or similar damaging of the warp straws, the purpose of which will be hereinafter more fully described. The marginal portions or edges of the seat and back sections 1 and 2 and the kick-apron 3 are encased or bound with fabric or cloth striping or binding material 4, in the fashion shown in the Figures 2 and 3, stitching 5, or other suitable securing means, being utilized to effect a positive and permanent connection of said binding to the adjacent portions of the elements to which the same is applied. Prior to the effecting of the stitching 5 or other securing means, however, I arrange pliable metal bars or strips 6 adjacent one or both of the corresponding portions of the faces of the straw matting and within the binding 4. In some instances, I may provide the relatively outer ends of these pliable metal strips with curved extensions 6' which round or extend about the adjacent corners of the straw matting material for distances along or throughout the transversal or opposite end binding 4. With the pliable strips so arranged and housed or encased by the binding 4, the stitching 5, or other binding connecting means, is applied. It will be thus seen that the longitudinal marginal portions or sides of the sections 1 and 2 and/or the kick-apron 3 will be equipped with a marginal stiffening medium characterized by its pliability and furthermore, by its ability to remain in a bent or flexed position. At this point, it may be stated that the mode of arranging or placing the pliable strips 6 upon the aforesaid portions of the straw matting sections or bodies and in the marginal binding 4 may be varied, as conditions or preference may dictate, insomlong as a strong and durable arrangement of the same, with respect to the straw matting, is attained. For example, it may be possible to secure the pliable strips 6 to the shield materials by effecting what is known in the art, as overcasted stitching. Moreover, it is to be understood that whereas I have herein shown the pliable or stay strips 6 as being extended along the longitudinal marginal portions of the sections 1 and 2 and the apron 3, said strips may also be extended completely along the opposite ends or transversal portions of these elements; likewise, additional strips 6 may be longitudinally disposed with respect to one or both of the faces of the intermediate portions of said sections 1 and 2 and/or the apron 3, in the fashion as illustrated in dotted lines in the Figure 1 and identified by the numeral 7, these intermediate longitudinal strips 6 being covered by a binding material,

which, in turn, is stitched or otherwise secured to adjacent portions of the sections.

In the herein shown and described embodiment of the invention, the seat and back sections 1 and 2 are depicted as being loosely or hingedly interconnected through the medium of fabric or other flexible pieces 8, the opposite sides of which extend over portions of the adjacent sides of said seat and back sections and are suitably connected or secured thereto, while the kick-apron is connected to the normally outer side of the seat section 1 by means of a like medium 9. In this way, it will be understood that the elements 1, 2 and 3 will be effectually interconnected in proper relation so that when the device, thus constituted, is used, it may be satisfactorily arranged in the fashion as illustrated in the Figure 1.

In production of seat covers or shields comprehending the invention, it is to be understood that the sections 1 and 2 and the apron 3 are made of maximum lengths, in order that they may be satisfactorily used to cover the adjacent or exposed surfaces of a seat and/or its back of maximum length. When, however, the device is to be used in connection with a seat or back which is of a length less than the lengths of the sections 1 and 2, said sections are arranged thereover so that the opposite ends of the same extend for substantially corresponding distances beyond either of the ends of the seat and/or the back (which latter elements are shown in the Figure 1 and are indicated by the numerals 10 and 11), as for example, in accordance with the arrangement shown in the Figure 3. At this time, the extended ends of the sections 1 and/or 2 are transversely flexed or folded over onto the adjacent end portions of the seat 10 or back 11 into snug engagement therewith. By reason of the provision of the pliable stay strips 6, it will be understood that the flexed or folded end engaging portions of the sections 1 and 2 will be retained in their flexed or adjusted positions. The character of the material of which the stay strips 6 are made is such that said strips will not only remain in their flexed or adjusted positions, but also, they will cause the flexed adjacent portions of the straw matting material to be likewise retained in the adjusted positions.

As hereinbefore described, the warp straws of the matting material from which the shields 1 and 2 are made, are disposed transversally of their sections, whereas the woof straws thereof, are longitudinally disposed. Consequently, it will be understood that with the transverse flexing of the extended opposite end portions of the sections 1 and 2, the resultant bend will be made in substantial parallelism to the warp straws and therefore, breakage or mutilation of these straws by reason of the bending of the sections, will be prevented. At the same time, an even and smooth corner overlap with respect to the adjacent end portions of the seat 10 or the back 11 will be permitted.

In instances of usage of the improved shield, where the length of the shield is greater than the length of the surface to be covered thereby, it will be appreciated that when the extended opposite ends of the shield are flexed and overlapped with respect to the opposite ends of the shielded surface, a snug embracing-like engagement of the shield with said surface or shielded element will be effected, and because of this, the shield will be positively positioned upon the

shielded element in a manner to prevent undue relative shifting movement thereof.

In event that the length of a seat supplied with the improved shield is less than the length of the sections 1 and 2, and consequently, less than the length of the kick-apron 3, it will be understood that the length of said kick-apron may be suitably adjusted by folding over the excess opposite end portions thereof in the fashion as is illustrated in the Figure 1; the pliable stay strips 6 with which said apron is equipped, effectually serving to retain the folded over excess portions in fixed folding position and hence, permitting the length of the kick-apron to be satisfactorily and permanently adjusted whereby the same will properly cover the exposed or forward edge portion of the seat 10.

It is desirable that the back section 2 shall be provided with a means which will permit of positive connection or securing thereof in position with respect to the back 11 and to accomplish this, I may and preferably do provide the outer or normally upper side of said section 2 with a fabric flap 12 of a width sufficient to permit of its overlapping or embracing-like engagement with and about the adjacent marginal portion of said back 11, as is shown in the Figure 1. The opposite end portions of this securing flap 12 are hemmed, as at 13, and within these hemmed portions, pliable metal stay strips 14 are arranged. Thus, when the securing flap 12 is embracingly engaged over the adjacent marginal portion of the back 11, the pliable stay strips 14 are bent upon themselves whereby they too, effect a snug embracing engagement with said adjacent portions of the back 11, and in so doing, it is obvious that the securing flap 12 will be positively retained in engagement with the back 11, and thus, will insure a positive yet disengageable connection of the section 2 to said back.

As hereinbefore stated, the application of the herein described invention is preferably effected in connection with shields or so-called seat pads made of straw matting, though it will be understood and appreciated by workers skilled in the art that the range of adaption of the invention is by no means confined or limited, in that devious

characters of shield or pad materials may be utilized, or if desired, combinations of such materials may be employed, as for example, seat shields or seat pads made of combinations of fabric and straw matting and the like.

From the foregoing, it will be understood that through the medium of my invention, I am enabled to produce a seat shield or seat pad which is more or less universal in its range of usage, especially, because of the fact that where the length of the shield is greater than the length of the seat or other surface to be covered thereby, said shield may be readily and conveniently adjusted upon itself to conform to the length of the receiving device, and in so doing, it will effect a smooth, even and satisfactory positioning with respect to such receiving device.

Manifestly, the constructions shown are capable of considerable modification, and such modification as is within the scope of my claims, I consider within the spirit of my invention.

I claim:

1. A seat pad comprising a flexible sheet-like body, pliable metal strips secured to the opposed sides of said body adjacent one of its faces, the outer ends of the respective metal strips being relatively inwardly disposed toward each other and arranged in juxtaposed relation to those portions of said face of the body adjacent its opposite ends and secured thereto, the free ends of the inwardly disposed portions of the metal strips being in relatively spaced relation whereby to permit of free flexing of that portion of said body intermediate of the same.

2. A seat pad comprising a flexible sheet-like body, pliable metal strips secured to the opposed longitudinal sides of said body adjacent one of its faces, the outer ends of the respective metal strips being inwardly curved and disposed toward each other and extended for comparatively short distances along the opposite end portions of the body, terminating upon said end portions of the body to effect their arrangement in relatively transversely spaced relationship, that portion of the flexible sheet-like body between the relatively spaced inwardly curved ends of the metal strips being capable of free flexing movement.

EDWARD WITTCOFF.
